Austin B. Snyder, Toledo, Ohio, assignor to Owens
Brush Company, Toledo, Ohio, a corporation of Ohio

Application July 10, 1952, Serial No. 20,538

Term of patent 14 years

(Cl. D86—10)

To all whom it may concern:

Be it known that I, Austin B. Snyder, a citizen of the United States, and a resident of the city of Toledo, in the county of Lucas, and State of Ohio, have invented a new, original, and ornamental Design for a Hairbrush or Similar Article, of which the following is a specification, reference being had to the accompanying drawing forming a part thereof.

In the drawing:

Figure 4 is an end elevational view, taken from the head or top end of the brush or similar article, as shown in Figures 1, 2 and 3; and

Figure 5 is an end elevational view, taken from the handle or bottom end of the brush or similar article, as shown in Figures 1, 2 and 3.

I claim:

The ornamental design for a hairbrush or similar article, as shown.

AUSTIN B. SNYDER.
